UNITED STATES PATENT OFFICE.

RICHARD SMITH, OF PHILADELPHIA, PENNSYLVANIA, ASSIGNOR TO MAC-KELLAR, SMITHS & JORDAN, OF SAME PLACE.

DESIGN FOR TYPE.

Specification forming part of Design No. 5,456, dated January 2, 1872.

To all whom it may concern:

Be it known that I, RICHARD SMITH, assignor to MacKellar, Smiths & Jordan of Philadelphia, in the county of Philadelphia, Pennsylvania, have originated and produced a new and original Design for Printing-Type, of which the following is a specification:

The nature of my design is fully represented

in the accompanying typographic impression, to which reference is made.

What I claim as my invention is—

The design for printing-type, as shown.

RICHARD SMITH.

In presence of—

GEO. WM. WITHAM,
C. F. HUCK.
